Fig. 3

Fig. 4

Fig. 5.

Fig. 6.

FIG. 1 is a front perspective view of a telephone booth or the like embodying my new design;

FIG. 2 is a bottom view;

FIG. 3 is a top view;

FIG. 4 is a front view;

FIG. 5 is a cross-sectional view taken at the line 5—5 of FIG. 4, and

FIG. 6 is a cross-sectional view thereof taken on the line 6—6 of FIG. 4.

The essential features of my design reside in the portions shown in full lines.

I claim:

The ornamental design for a telephone booth or the like, substantially as shown and described.
